UNITED STATES PATENT OFFICE

LEWIS T. BORINSON, OF SCHENECTADY, NEW YORK, ASSIGNOR TO GENERAL ELECTRIC COMPANY, A CORPORATION OF NEW YORK

SOUND-PICK-UP DEVICE

Application filed February 28, 1930. Serial No. 432,220.

My invention relates to sound pick-up devices and particularly to such pick-up devices which cause a small mirror to vibrate in response to sound waves. It is the object of 5 my invention to provide an improved device of this character which shall be simple, sensitive, efficient and economical to manufacture.

My invention will be better understood from the following description taken in connection with the accompanying drawing, and its scope will be pointed out in the appended claims.

Referring to the drawing, Fig. 1 is a plan view of an embodiment of my invention drawn to an enlarged scale; Fig. 2 is a transverse cross-sectional view thereof; Fig. 3 is a fragmentary detail view drawn to a still larger scale; and Fig. 4 shows a modified form of the detail. The sound actuated member or diaphragm 1 is shown clamped between two rings 2 and 3 by means of a plurality of screws 4. I preferably construct the diaphragm of mica and the rings of steel, the mica being under tension such that its natural 20 period of vibration is above the audible range. One method of so tensioning the mica is to insert the rings and mica diaphragm with the clamping screws loosened in a bath of liquid air and while thus immersed to tighten the 25 screws. Upon being restored to room temperature the mica which has a smaller coefficient of expansion than steel will be given the required tension. Secured to the ring 2 by the 30 screws 5 is the plate 6 having the central offset portion 7 fitting within the interior of the ring 2. Across the central opening 8 of the plate 6 is the torsion strip 9 which is secured, as by soldering, to the lower face of plate 6 while under tension. Attached to one side of 35 the torsion strip and approximately at the middle of the ring is the small mirror 10 which by its angular vibration is adapted for the reflection of a light beam on a moving sensitive film in the case that a sound recording is being made or is directed into a photoelectric cell in the case of apparatus for transforming sound vibrations into electric vibrations. The vibratory movement of the diaphragm 1 is communicated to the torsion strip 40 9 by means of the small pin 12 which it will

be noted engages the torsion strip adjacent one edge thereof so that the vibratory movements of the diaphragm cause angular vibrations of the torsion strip.

For the purpose of preventing the torsion strip from being moved bodily and for limiting the vibrations of the strip to angular movements I have provided the abutment member 14 which is adjustably mounted on the ring 6 and which has the two arms 15 extending to the rear of the torsion strip. Each arm 15 is shown having an inset 16 provided with a knife edge 17 which extends longitudinally of the strip and which engages the same midway between its two edges. The abutment member is adjustably mounted upon the slide 19 and by means of the adjusting screw 20 may be raised or lowered so as to be moved into proper engagement with the torsion strip. The slide 19 is attached to the plate 6 by the two screws 21 which pass through slotted openings therein and by means of the thumb screw 22 carried by the block 23 the slide and the abutment member may be adjusted transversely of the torsion strip. While I have shown and described the abutment member as having the knife edge members 16 for engaging the torsion strip, I may in certain cases use small pins 24, see Fig. 4, instead of the knife edge members, which pins will make point contact with the torsion strip. With this construction it will be seen that the vibratory movements of the diaphragm are transmitted through the small pin 12 to the torsion strip where the movement is converted into angular vibration. By the provision of the abutment member having its knife edges engaging the torsion strip intermediate the edges thereof the movement of the torsion strip is limited to angular movement which thereby reaches a maximum value for a given vibratory movement of the diaphragm.

I have chosen the particular embodiment described above as illustrative of my invention and it will be apparent that various modifications may be made without departing from the spirit and scope of my invention which modifications I aim to cover by the appended claims.

What I claim as new and desire to secure by Letters Patent of the United States, is,—

1. A sound pick-up device comprising a torsion member, a mirror supported thereby, a sound actuated member connected with said torsion member to cause a torsional vibration thereof, and means arranged to engage the torsion member for limiting the movement thereof to torsional vibration.
- 10 2. A sound pick-up device comprising a torsion member, a mirror supported thereby, a diaphragm, means connecting the diaphragm with the torsion member at a point adapted to cause torsional vibration thereof and means associated with the torsional member for preventing displacement bodily thereof without restricting the torsional vibration thereof.
- 20 3. A sound pick-up device comprising a torsion strip, a mirror secured thereto, a diaphragm, means connecting the diaphragm with the strip at a point adjacent one edge of the strip, and an abutment member arranged to engage the strip at a point intermediate its edges.
- 30 4. A sound pick-up device comprising a torsion strip, a mirror secured thereto, a diaphragm, means connecting the diaphragm with the strip at a point adjacent one edge of the strip, and an abutment member having a knife edge arranged to engage the strip midway between its two edges and to extend longitudinally thereof.
- 35 5. A sound pick-up device comprising a torsion strip, a mirror secured thereto, a diaphragm, means connecting the diaphragm with the strip at a point adjacent one edge of the strip, an abutment member having a pair of knife edges extending longitudinally of the strip arranged to engage the strip at opposite sides of the connecting means, and means for adjustably supporting the abutment member.

In witness whereof, I have hereunto set
45 my hand this 27th day of February, 1930.

LEWIS T. ROBINSON.
